CRUTCH

David Lockett, 574 Hyacinth Place,
Highland Park, Ill. 60035

Filed Feb. 2, 1967, Ser. No. 5,662

Term of patent 14 years

(Cl. D88—5)

FIG. 1.

FIG. 2.

FIG. 3.

FIG. 4.

FIG. 5.

FIGURE 1 is a perspective view of a crutch, embodying my new design;

FIGURE 2 is a front elevation view;

FIGURE 3 is a side elevation view;

FIGURE 4 is a top plan view; and

FIGURE 5 is a sectional plan view taken along line 5—5 in FIGURE 4.

I claim:

The ornamental design for a crutch, as shown.
